PROTECTIVE GRATING

Filed April 12, 1923

UNITED STATES PATENT OFFICE

SIMON B. HESS, OF NEW YORK, N. Y.

PROTECTIVE GRATING

Application filed April 12, 1923. Serial No. 631,738.

This invention relates generally to burglar alarm systems of the electrical protective circuit type and particularly relates to the improved means for holding circuit-completing gratings in operative position during the hours when the building is unoccupied.

The invention consists in the provision of improved means for establishing electrical contact between contact members carried by a protective grating and corresponding contact members mounted on a door or window casing and forming terminals for a normally closed circuit protective system. The invention also includes means for readily placing the grating in or removing it from operative position and for holding it securely in place when in protecting position.

In the drawings, in which a preferred form of the invention has been selected for illustration,

Figure 1 is an isometric view of a portion of a protective grating and showing means embodying the invention for holding the grating in place.

Figure 2 is a view in vertical section of a portion of the device in Figure 1 showing circuit closers and grating holding members embodied in the invention.

Figure 3 is a view in horizontal section of the device shown in Figure 2.

Referring to the drawings for a more detailed description of the invention, the vertical frame member of a window casing is shown at 5. A vertical wood strip 6 is attached to the face of the frame member 5 in any suitable manner and carries an outstanding post 7 having an enlarged head 8. The strip 6 is also supplied with contact plungers 9 and 10 mounted to protrude through openings in plates 11 and 12 and tending to be projected outwardly by the action of springs 13 mounted in recesses at the rear of the plates 11 and 12 and bearing against the head of the contact plungers 9 and 10.

The plates 11 and 12 and the contact plungers 9 and 10 together form terminals of a pair of conductors included in a protective circuit installation which forms no part of the present invention and is accordingly not illustrated.

A grating formed of wood for the sake of lightness in weight and ease in handling is provided to be mounted in place across each door and window opening when the building is left unoccupied, as during the night-time hours. The grating includes vertical side frame members 14 and intermediate vertical bars 15 crossed by the transverse bars 16 to form a grating or grid.

The inner faces of the side frame members 14 of the grating are provided with contact plates 17 and 18 so positioned as to engage the contact plungers 9 and 10 on the window frame when the grating is in position thereon. The contact plates 17 and 18 form terminals for conductors 19 embedded in the bars 15 and 16 and strung back and forth and up and down with the bars of the grating to provide a partial circuit terminating at the opposite sides of the grating in the contact plates carried by the side frame pieces 14. It will be seen that this arrangement of the conductors carried by the grating insures the rupture of the circuit and brings about the actuation of alarm or other indicating mechanism in the event that one of the grating bars is broken by an unauthorized entry through the protected opening.

In order to hold the protective grating in place in guarding relation to the window or other opening, the side frame members 14 of the grating are provided with openings 19' closed at their outer ends by plates 20 having openings 21 therein of an inverted key shaped formation. It will be seen that by passing the enlarged lower ends of the openings 21 in the plates 20 of the grating over the enlarged heads 8 of the posts 7 and then lowering the grating to bring the more restricted upper ends of the openings 21 into engagement with the posts 7 to the rear of the heads 8, the gratings are securely locked in position on the supporting posts 7. The length of the posts 7 back of the heads 8 is such that the contact plates 17 and 18 carried by the grating engage and depress the contact plungers 9 and 10 carried by the strip 6 on the window casing or frame against the pressure of the springs 13. The result of this is that the springs 13 hold the contact plung-

ers 9 and 10 in close contact with the contact plates 17 and 18 and also hold the frame in close and rigid engagement with the under surfaces of the enlarged heads 8 on the posts 7.

The grating is readily placed in protecting position at the close of the day and as readily removed therefrom when the building is again opened and occupied, these operations 10 being greatly facilitated by the referred to construction of the pin and slot attaching means between the grating and the frame of the door or window to be protected.

In order to provide a safeguard against 15 the removal of the wood strips 6 and the possibility of thereby avoiding a breaking of the circuit through the grating or barrier, circuit closers 22 are set into the vertical frame members 6 as indicated in Figure 2 of the 20 drawings. By this arrangement the spring pressed contact member 23 of the circuit closer is normally held out of contact with the contact 24 by engagement with the window frame 5. Should the frame member 6 25 be pried from its position the contact member 23 makes contact with the point 24 and closes a short or bridge circuit with relation to the circuit included in the grating circuit. The short circuit thus obtained manifests 30 itself in any desired manner at the central office, through taking advantage of the decrease in resistance between the bridge circuit and that including the great length of conductor carried by the grating.

35 What is claimed is:—

1. A burglary preventing device comprising a grating, means for removably attaching said grating to a window frame, interlocking pin and slot members on the frame and grating for holding the grating in place, 40 interengageable electrical contacts mounted on said frame and said grating, one of said contacts being spring-pressed for urging said pin and slot members into firm engagement with each other to maintain said grating in 45 position on said frame, an electrical conductor passing through the grating and connected with the grating-carried contacts, and a protective circuit connected with the frame-carried contacts.

2. A burglary preventing device comprising a grating adapted to be removably attached to a window frame, interlocking pin and slot members on the frame and the grating 55 for holding the grating in place, the pins being provided with heads, a pair of contacts carried by the grating, a pair of contacts carried by the frame, a pair of springs holding the frame-carried contacts in engagement 60 with the grating-carried contacts, said springs serving also to maintain the grating in firm engagement with the heads of the pins, an electrical conductor passing through the grating and connected with the grating-carried contacts, and a protective circuit ex-

tending through grating and connected with the frame-carried contacts.

3. A burglary preventing device comprising a grating means for removably attaching said grating to a window frame, means for holding the grating in place including a member provided with a key-hole slot and also including a pin member provided with an enlarged head for engagement with said slot, interengageable electrical contacts 70 mounted on said frame and said grating, one of said contacts being spring-pressed for urging said pin and slot members into firm engagement with each other to maintain said grating in position on said frame, an electrical conductor passing through the grating and connected with the grating-carried contacts, and a protective circuit connected with the frame-carried contacts. 75

4. A burglary preventing device comprising a grating adapted to be removably attached to a window frame, interengaging means on said grating and frame for removably holding the grating on the frame, a pair of electrical contacts carried by each of said gratings and said frame, one of said pairs of contact members being movable and spring-pressed respectively toward the other of said pairs of contact members, said spring-pressed contacts urging said grating-carried means 90 into interengaged position with said frame-carried means, an electrical conductor passing through the grating and connected with the grating-carried contacts, and a protective circuit 95 connected with the frame-carried contacts. 100

5. In a burglary preventing device, the combination with a grating support secured to a window frame, of a grating, means for detachably securing said grating to said support, interengageable electrical contacts mounted on said support and said grating, and electrical conductors passing through the grating and connected with the grating-carried contacts, stationary and movable contacts mounted on said support, said movable contact being provided with means for holding said movable contact out of engagement with said stationary contact while the support is in position on the frame and also for permitting said movable contact to engage said stationary contact upon removal of said support from said frame, and a protective circuit connected with said support-carried contacts and with said stationary and movable contacts. 110 115

6. In a burglary preventing device, the combination with a grating support secured to a window frame, of a grating, interengaging means on said grating and support for removably holding the grating on the support, interengaging electrical contacts mounted on said grating and said support, one of said contacts being spring-pressed for urging said interengaging means into firm engagement 120 125 130

to maintain said grating in position on said support, an electrical conductor passing through the grating and connected with the grating-carried contacts, stationary and movable contacts mounted on said support, said movable contact being provided with means for holding said movable contact out of engagement with said stationary contact while the support is in position on the frame and
5 also for permitting said movable contact to engage said stationary contact upon removal of said support from said frame, and a protective circuit connected with said support-carried contacts and with said stationary and
10 movable contacts.

In testimony whereof I affix my signature.
